UNITED STATES PATENT OFFICE.

THOMAS RODMAN, OF YOUNGSTOWN, OHIO, AND FRANK M. STEVENSON, OF SHARON, PENNSYLVANIA, ASSIGNEES TO THE PENNSYLVANIA TANK CAR COMPANY, OF SHARON, PENNSYLVANIA, A CORPORATION OF OHIO.

CARRY-IRON.

1,273,541.

Specification of Letters Patent. Patented July 23, 1918.

Application filed January 7, 1918. Serial No. 210,630.

To all whom it may concern:

Be it known that we, THOMAS RODMAN and FRANK M. STEVENSON, citizens of the United States, and residents of Youngstown, 5 in the county of Mahoning and State of Ohio, and Sharon, in the county of Mercer and State of Pennsylvania, respectively, have invented a new and useful Improvement 10 in Carry-Irons; and we do hereby declare the following to be a full, clear, and exact description thereof.

This invention relates to carry irons, and more particularly to carry irons adapted to be secured to a center sill of a car to support 15 the forward end of a coupler shank.

One of the principal objects of this invention is to form carry irons of such shape and construction that they may be made entirely of forged metal, and still be of such 20 strength and resiliency as to be far superior to any carry irons heretofore constructed.

A still further object of our invention is to provide a carry iron of the class described which will consist of very few parts, and so 25 be cheaper to manufacture, more durable and less liable to become out of order.

Another object of our invention is to provide chafing plates or stops, which will limit lateral movement of the coupler shank.

It will be readily understood that various 30 changes in design and details of structure may be made within the skill of the ordinary mechanic in the art, without departing from our invention as defined in the ap-

35 pended claim.

In the drawings:

Figure 1 is a side elevation, partly in section, of a portion of a drawhead embodying the invention;

40 Fig. 2 is a front elevation of same; Fig. 3 is a sectional plan view of the carry iron on the line 3—3 Fig. 4;

Fig. 4 is a front elevation of same; and Fig. 5 is a section on the line 5—5 Fig. 4.

45 Like symbols of reference herein indicate like parts in each of the figures of the drawings.

Referring more particularly to the drawings, the letter A designates the device as a 50 whole which is held between sill members 1. Our improved carry iron or saddle member A is composed of forged metal and comprises a bottom or base 2 and upright arm

portions 3 forming a substantially U-shaped member. The device is so shaped as to form 55 an angle body, the vertical flange of which is disposed to the front, and the other flange of which is disposed within the sill to support the device.

It will also be understood that while the 60 angle provides supporting and securing flanges for supporting the device in position, it also adds materially to the strength of the device and permits a lighter construction than would be possible if such angle 65 shape were not used.

Chafing plates or stops 4 of angle construction are secured to the flanges of the 70 upright arms 3 which extend within the sill by bolts 5 passing through apertures 6. The bolts 5 also pass through the sills 1 and serve to secure the whole device in position.

The device is adapted to support and carry the forward end of a shank of a coupler 75 7 which is adapted to have a sliding movement thereon, and the shank 8 of the coupler is adapted to engage the stops 4 to limit the movement thereof.

One of the advantages of making the 80 carry iron of forged metal is that the strains and shocks to which it is subjected will not cause it to crack or break and to give it a general resiliency to allow for the many twists and pulls caused by the coupling of cars and their movement over rough roads. 85

Having thus described our invention, what we claim is:

The combination with a center sill for a 90 railway car, of a substantially U-shaped carry iron for couplers composed of forged metal, said carry iron being angle shaped in cross section and having its one flange disposed vertically over the end edge of said center sill and its other flange directed longitudinally along the inner face of said 95 sill so as to support the device, and means for securing said carry iron in position on said center sill.

In testimony whereof, we, the said THOMAS RODMAN and FRANK M. STEVENSON, 100 have hereunto set our hands.

THOMAS RODMAN.

FRANK M. STEVENSON.
